CLAIM

The ornamental design for a sterilization device, as shown and described.

DESCRIPTION

FIG. 1 is a top, front, right perspective view of a sterilization device showing our new design;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right perspective view of the sterilization device of FIG. 1 shown in a first condition of use; and,

FIG. 10 is a top, front, right perspective view of the sterilization device of FIG. 1 shown in a second condition of use.

The broken lines in the drawings depict portions of the sterilization device that form no part of the claimed design. The broken lines showing a base in FIGS. 9 and 10 depict environmental structure that forms no part of the claimed design. All broken lines for no part of the claim.

1 Claim, 10 Drawing Sheets
